BACK-LASH TAKE-UP FOR GUN ELEVATING MECHANISM

Filed Jan. 19, 1944

UNITED STATES PATENT OFFICE

2,436,379

BACKLASH TAKE-UP FOR GUN ELEVATING
MECHANISM

George I. Chinn, Detroit, Mich.

Application January 19, 1944, Serial No. 518,808

6 Claims. (Cl. 89—41)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention pertains to a novel device for taking up the gear backlash in guns which are balanced about the trunnions for the purpose of operation with a gyro stabilizer.

In combat tanks a gyro stabilizer is used for maintaining the gun on the target during motion of the vehicle. No backlash take-up is required when the gun is so used. However, when the vehicle is not in motion and the gun is employed as a stationary field piece, the elevation of the gun is manually controlled and some backlash take-up means is necessary. The object of the present invention is to use a portion of the gyro stabilizer system, which is otherwise inactive at this time, for taking up the backlash.

The gyro stabilizer system includes a hydraulic cylinder with a piston for effecting the elevation of the gun. The gyroscope is active on a teeter valve for admitting pressure fluid to one side or the other of the piston. Each valve stem of the teeter valve is actuated by a coil, and the two coils are energized varyingly from the gyroscope mechanism.

The invention described herein comes into use only when the gyroscopic system is not in use. The invention provides a separate circuit for energizing only one of the coils in such a manner that the pressure fluid is admitted to the cylinder on that side of the piston which exerts a downward force on the breech end of the gun at the point beyond the horizontal pivotal mounting. This force is comparable to the downward force which would be produced by a counterweight used for the purpose of making the gun breech-heavy.

An illustrative embodiment of the invention is disclosed in the following description and in the accompanying drawings in which the single figure is a schematic sectional view of the apparatus combined with a wiring diagram.

The conventional gun gyro-stabilizer system will first be described. The gun 1 is mounted on trunnions 2. Above or below the gun is a pivotally mounted hydraulic cylinder 3 containing a piston 4 with a rod 5 pivotally connected to the gun at a point 6 behind the trunnions.

The lead-in wire 10 from a suitable grounded source of potential is branched at 11 to contain a fluid pump motor 12 for driving the two fluid pumps comprising gears 35, 36, and 37, and branch 11 is finally grounded at 13. Another branch 14 contains a gyro motor 15 and is also

2

grounded at 13. The wire 10 contains a master switch 16 between the source and the branch 11. Between the branches 11 and 14 is a gyro circuit switch 17 inserted in a continuation 10' of the line 10 connected at 18 to the grounded side of the branch 14. The extension 10' contains a pilot light 19.

To the extension 10' is connected a resistor 20, with a switch 21 interposed. Another resistor 22 extends from the point 18 to a point 23 between the resistor and the switch 21. Two spaced sets 24 and 25 of contactor blades known as a silverstat are provided. These are interconnected at one end by a conductor 26 and are normally separate at their remaining ends 27. Between the sets is an actuator 28 adapted to bring into mutual engagement a varying number of blades at one or the other side of the actuator. The actuator is operated from a gyroscope system (not shown) mounted on the vehicle. An adjustable contact 29 on the resistor 22 is joined by a conductor 30 to the conductor 26 at the space between the sets 24 and 25.

The hydraulic system includes a pump body 31 having two parallel main passages 32 and 33 disposed within a reservoir 34. Fluid is drawn from the reservoir and discharged through the passages by two pumps comprising gears 35 and 36 and 37. The passages 32 and 33 are connected by lines 38 and 39 respectively to the cylinder 3 at opposite sides of the piston 4. Beyond their connections to the lines 38 and 39, the passages 32 are formed with valve seats 32' and 33' communicating freely with the reservoir 34. Co-operating with the valve seats is a teeter valve comprising a magnetic bar 43 pivotally mounted intermediate its ends on the fulcrum 43', and having seating valve stems 32a and 33a extending from the opposite end of the bar to the valve seats. By the tilting of the bar 43, one valve is opened wider while the other is correspondingly restricted.

The magnetic teeter bar 43 is operated by coils 46 and 47 wound upon cores 44 and 45 respectively located adjacent opposite ends of the bar 43 each coil having one end connected to a different end of conductor 26 by a conductor 46a or 47a. The remaining ends of the coils are grounded at 48. Around the core 44 is a buffer coil 49 joined by a conductor 50 to an adjustable contact 51 on the resistor 20. The conductor 50 contains a switch 52 which is automatically closed on the recoil of the gun. The switch 52 is mounted upon a stationary part of the gun and is normally held open by engagement with

the breech (not shown) of the gun. Recoil of the breech moves the latter away from the switch and closes the same.

The operation of the system thus far described, which is not new in the art will now be explained. The gyroscope system on the vehicle determines the position of the actuator 28, the resistance in sets 24 and 25 of silverstat blades, and the relative resistance of the coils 46 and 47. With the switches 16 and 17 closed so that current flows in the system, the coil carrying the larger current will move the corresponding valve stem 32^a or 33^a towards its seat to reduce the aperture connecting the corresponding passage and its by-pass. Thus, the pump 35, 36, 37 will force fluid to one side of the piston 4, while the other side will be opened through the unobstructed by-pass to the reservoir 34.

On the recoil of the gun, the switch 52 closes and energizes the coil 49. This closes the valve seat 33' so that fluid is delivered beneath the piston 4 in the cylinder 3 to cushion the recoil.

As is conventional with guns of the type provided with a gyro stabilizer, manually actuated mechanical means is provided for moving the gun in elevation when the gyro stabilizer is not in use. This means is shown in the drawings as comprising an arcuate rack 85 mounted vertically on the gun 1 and a crank operated gear train 83 having a pinion 84 for engaging the rack 85. As also is conventional with guns of this type, the gear train is adapted to be disengaged from the rack 85 when the gyro stabilizer is in use. As is well known, the gyro stabilizer and the manually actuated elevating means are not used simultaneously.

Conventional mechanical elevating systems, as is also well known, inherently have an appreciable amount of backlash, i. e., a play or movement in the connected parts resulting from looseness, which is particularly disadvantageous when the gun is substantially balanced at the trunnions as is the usual gyro stabilized gun. In accordance with the present invention, the gyro stabilizer system is modified to permit it to be utilized during manual operation of the mechanical elevating means, when otherwise it would not be in use, to take up the backlash in the gearing of the mechanical elevating means. The modification, a description of which follows, is denoted by the solid lines of the wiring diagram.

Referring to the drawings, a conductor 60 is connected to the extension 10' and the conductor 47^a through a resistor 64 and switch 61. When the mechanical elevating system is brought into use, the switch 17 or switch 21, or both, are opened automatically or manually to disconnect the gyro control circuit. The switch 61, which remains open when the gyro stabilizer is used, is closed when the mechanical elevating system is brought into use. Switch 16 remains closed during both operations. It thus will be seen that during the use of the mechanical elevating system, the fluid pump motor 12 which drives the fluid pump is energized, and by the closing of switch 61 there is also energized the coil 47 which actuates the teeter valve stem 32^a, causing the latter to move towards valve seat 32' thereby relatively restricting the aperture leading to passage 32 and causing downward fluid pressure to be exerted on the piston 4. The resulting downward pressure or biasing force exerted upon the gun by the pressure applied to the top of the piston 4 takes up all backlash present in the mechan-

ical elevating mechanism. Movement of the gun by reason of this force is prevented by the irreversible functioning of the elevating gearing 83. However, this force or downward fluid pressure on the piston 4 is readily overcome by manual operation of the mechanical elevating mechanism in obtaining depression of the muzzle of gun 1, the fluid in cylinder 3 above the piston 4 and in line 39 then being escapable through the restricted aperture from passage 32 to the reservoir 34.

An oppositely acting or interlocking switch 62 may be inserted in the conductor 47^a between the blades 24 and the conductor 60 to cut out the blades when the backlash take-up system is to be energized. However, the switch 62 is not always essential since sufficient current to energize the coil 47 will remain even if current flows elsewhere. The voltage on the coil 47 is controlled by a dropping resistor 64 in the conductor 60. The energized coil 47 thus controlled causes relative restriction to a degree of the aperture at the valve seat 32' and corresponding opening to a degree of the aperture at the seat 33' to deliver the resultant pump pressure to the top of the piston 4 and a resulting downward pressure on the breech of the gun.

While a specific embodiment of the invention has been shown and been described, it will be understood that various alterations may be made without departure from the spirit of the invention as indicated by the appended claims.

What I claim is:

1. In combination with a trunnion-mounted gun of the type having alternately operable manually-actuated mechanical means and automatically-controlled fluid pressure means for selectively positioning the gun about its trunnion axis, means engageable during operation of the said mechanical means for modifying the said fluid pressure means to provide a positioning force biasing said gun in one direction only to take up backlash in said mechanical means.
2. In combination with a trunnion-mounted gun of the type having alternately operable manually-actuated mechanical means and automatically-controlled fluid pressure means for selectively positioning the gun about its trunnion axis, means for modifying said fluid pressure means to provide a positioning force biasing said gun in one direction only to take up backlash in said mechanical means.
3. In combination with a trunnion-mounted gun of the type having alternately operable manually-actuated mechanical means and automatically-controlled fluid pressure means for selectively positioning the gun about its trunnion axis, said automatically-controlled fluid pressure means comprising piston means operatively connected to the gun, a source of fluid pressure, a gyro-controlled circuit, and valve means responsive to said gyro-controlled circuit for controlling the application of the fluid pressure to oppositely-directed areas of the piston means, means for actuating the valve means to apply fluid pressure to only one of the oppositely directed areas of the piston means and means for disconnecting said gyro-controlled circuit during operation of said manually-actuated mechanical means.
4. In combination with a trunnion-mounted gun of the type having alternately operable manually-actuated mechanical means and automatically-controlled fluid pressure means for selec-

tively positioning the gun about its trunnion axis, said automatically-controlled fluid pressure means comprising a cylinder, a piston mounted in said cylinder and adapted for connection to a trunnion-mounted gun, a member having a pair of passages connected respectively to said cylinder at opposite sides of said piston, a fluid reservoir in communication with said passages, a pump for transferring fluid from said reservoir to said passages, a by-pass from each passage to said reservoir, a magnetic teeter valve having a rocker with valve stems adapted to selectively obstruct said by-passes from the corresponding passages, a pair of coils acting on said valve, and a gyro-actuated circuit for selectively energizing said coils, a circuit external to the first circuit for energizing one of the coils to close the by-pass of the passage that exerts a downward force on said piston, and means for disconnecting said gyro-actuated circuit and for closing said external circuit when the gun is to be manually positioned.

5. In combination with an automatically-controlled fluid pressure means for selectively positioning a gun about its trunnion axis comprising fluid pressure means for applying a force on a gun in either direction about its trunnion axis, electrically actuated valve means for controlling the direction of the force on the gun, and a gyro-actuated circuit for controlling said valve means, a circuit external to said gyro-actuated circuit for actuating said valve to apply a force on the gun in one direction only, and means for disconnecting the gyro-actuated circuit and closing the said external circuit whereby said fluid pressure means may be used to take up backlash when the gun is mechanically elevated. 35

6. In combination with an automatically-controlled fluid pressure means for selectively positioning a gun about its trunnion axis comprising a cylinder, a piston mounted in said cylinder and adapted for connection to a trunnion-mounted gun, a member having a pair of passages connected respectively to said cylinder at opposite sides of said piston, a fluid reservoir in communication with said passages, a pump for transferring fluid from said reservoir to said passages, a by-pass from each passage to said reservoir, a magnetic teeter valve having a rocker with valve stems adapted to selectively obstruct said by-passes from the corresponding passages, a pair of coils acting on said valve, and a gyro-actuated circuit for selectively energizing said coils, a circuit external to the first circuit for energizing one of the coils to close the by-pass of the passage that exerts a downward force on said piston, and means for disconnecting said gyro-actuated circuit and for closing said external circuit when the gun is to be manually positioned.
